UNITED STATES PATENT OFFICE.

JOHN M. CHENEY, OF SOUTHBRIDGE, MASSACHUSETTS.

LOOM-SHUTTLE SPINDLE.

SPECIFICATION forming part of Letters Patent No. 394,458, dated December 11, 1888.

Application filed March 27, 1888. Serial No. 268,699. (No model.)

To all whom it may concern:

Be it known that I, JOHN M. CHENEY, of Southbridge, county of Worcester, State of Massachusetts, have invented an Improvement in Loom-Shuttle Spindles, of which the following description, in connection with the accompanying drawings, is a specification, like letters on the drawings representing like parts.

10. In the employment of mule-cops on loom-shuttle spindles as now made the yarn fails to unwind freely, and a considerable portion of the cop goes into waste.

The mule-spindle is tapering and the cop-tube is uniformly cylindrical, and as a result thereof the yarn winding from the cop-tube on the spindle from the base of the cop toward its nose drops off the larger cylindrical body of the cop-tube upon the smaller spindle, 20 thus leaving, as it were, a shoulder or offset in the yarn portion of the cop which is of less diameter than the hole in the cop-tube.

Shuttle-spindles are usually split from near the spindle-head to nearly the point of the spindle, and the sides are set open or apart, thus making an expansible portion to hold the cop frictionally and prevent the cop sliding on the spindle or from flying off when the shuttle is stopped in the shuttle-box.

30. In putting a mule-cop such as described on a loom-shuttle spindle of the kind referred to the spindle, as the cop-tube is pushed into place near the head of the spindle, acts to stretch the cop of yarn at that portion thereof where the hole therein is of less diameter than the cop-tube next to it, which cop-tube is supposed to fit the shuttle-spindle, and the coils of yarn at the point where the cop is so stretched or expanded become embedded one 35 coil closely into another, so that when weaving off the cop the thread breaks at this point and the balance of the cop is thrown into what is called "waste."

Should the expansion of the spindle next 45 the inner end of the cop-tube be so little as not to stretch the cop of yarn injuriously, as stated, but leave the yarn free to run off for weaving, then the cop-tube would traverse the spindle endwise when the yarn shall have run 50 off to near the inner end of the cop-tube and the yarn would be tangled and would break.

In my efforts to overcome these difficulties

I have so constructed the spindle as to hold the cop from its nose back to about the longitudinal center of the cop, while from such 55 part of the top of the inner end of the cop-tube the spindle exerts but very little, if any, pressure, and to keep the cop in place on and prevent it slipping longitudinally on the spindle when the cop is being unwound to a 60 point back of the largest diameter of the split spindle I have provided the spindle with a cop-tube holder, on which the cop-tube is forced, and which alone acts to hold the cop-tube firmly in place, permitting the yarn to 65 be all woven off. The shuttle-spindle is also provided with a shoulder or projection to form a stop, whereby the extent of movement of the cop-tube toward the head of the spindle is limited, so that when the spindle is turned 70 in the shuttle the usual spring will not strike the cop.

Figure 1 shows a sufficient portion of a shuttle-body, partly broken out, together with a spindle and cop-tube holder embodying my 75 invention, to enable the same to be understood, the drawing by dotted lines showing not only the outline of the cop and cop-tube, but also a portion of the spindle as it will be when raised partly to receive a cop. 80 Fig. 2 in elevation shows the spindle with my improved holder. Figs. 3 and 4 show spindles with modified forms of holders.

The shuttle-body A has a pin, B, on which is pivoted the head a of the shuttle-spindle 85 a', which is retained in either of its two usual positions by the usual spring, C.

The spindle a' is herein shown as split and bulged to form a spring, which by its inherent expansion holds the cop frictionally from 90 the center of its length to its point on the spindle. Usually the two halves of the spindle are so bent that they bow outwardly from near the point of the spindle nearly to the head of the spindle, the expansion of the 95 spindle at a point opposite the inner end of the cop-tube being sufficient to hold the latter in place and prevent it sliding on the spindle, and, as stated, this expansion strains the yarn in the cop at and beyond the end of the 100 cop-tube and mats and tightens it together in such manner as to prevent the free delivery of the yarn as the latter, being unwound, approaches the outer end of the cop-tube. When

the expansion of the spindle is not depended upon to hold the cop-tube in place, I need only to expand the spindle from near its point back to a point outside near the inner 5 end of the cop-tube, and consequently the spindle does not stretch outwardly, or injuriously so, the yarn of the cop, but leaves it in its soft-wound condition as taken from the mule-spindle. When the cop and its tube are 10 at first crowded down upon a spindle the expansion of which is carried substantially to the head of the spindle, the first application of the cop to the spindle is not that which stretches the cop injuriously outwardly, for 15 when the cop is of full length it acts on a large part of the spindle; but when the cop is so far unwound that but part of the spindle is inclosed by the cop then the spindle gradually expands and gradually stretches 20 the cop more and more at the end of the cop-tube, and so draws the coils of yarn together, as stated. To avoid this outward straining of the yarn of the cop near the end of the cop-tube, and also the slipping of the cop-tube on the spindle, I have fixed to the spindle, as herein shown, a cop-tube holder consisting, essentially, of a spring or springs, as 25 d, confined at one end to the spindle.

Preferably the cop-tube holder will be attached to the spindle at a short distance from its head, the inner ends of the springs terminating, as shown in the drawings, at a shoulder or projection, as d', the latter serving as a stop for the cop-tube.

35 The inner or free ends of the springs of the holder are embedded in pits, as d², formed in the spindle, and for the best results the springs will be in line of the slit in the spindle, as thereby the strain is less on the springs 40 of the holder; but the springs may be placed at the sides of the spindle, as in Fig. 4.

Fig. 3 shows a modification of my invention in which the cop-tube holder consists of one spring-arm, d, soldered or otherwise fixed 45 to the spindle next the projection d', shown as a pin inserted into or connected to the head of the spindle. When the spindle is turned out, as partially shown by dotted lines, Fig. 1, the end of the spring C meets the spindle between its head a and the stop d' and does not touch the cop-tube or cop.

I do not desire to limit my invention to the particular method shown for confining the holder to the spindle, as the springs may be

modified in construction and be brazed, soldered, or otherwise fixed on the spindle.

I am aware that split spindles are commonly used in loom-shuttles; also, that springs have been used to hold bobbins upon spinning-spindles and shuttle-spindles which were 60 not split.

In all split spindles known to me and employed in loom-shuttles the bulge of the spindle is carried sufficiently far toward the head of the spindle to make the said bulge effective in holding the cop-tube; but herein such is not the operation of the split spindle, for my improved split spindle is so constructed that the bulge part thereof is not extended back toward the head of the spindle far enough to enter the cop-tube, but only sufficiently far to hold the front end of the cop, leaving that part of the cop next the end of the cop-tube free from any outward expansion whatever due to the split or bulge part 75 of the spindle, the holder employed by me being of sufficient strength to effectually prevent the sliding of the cop-tube on the spindle, the friction between the cop and cop-tube being sufficient to hold the cop from longitudinal motion, even after the main body of 80 yarn forming the cop has been so far unwound as to uncover the most expanded portion of the split spindle.

I claim—

1. The combination, with a loom-shuttle and its split spindle to hold a cop thereon frictionally, of a spring cop-tube holder connected thereto, the said holder receiving upon it the cop-tube and acting wholly to retain the latter and the yarn between it and the bulged part of the spindle from sliding on the spindle, substantially as described.

2. The shuttle-body, its spring, and the split spindle having the shoulder d' near its head, combined with the spring cop-tube holder, the latter acting to hold the cop-tube, as described, while the said shoulder forms a stop for the lower end of the cop-tube, substantially as described.

In testimony whereof I have signed my name to this specification in the presence of two subscribing witnesses.

JOHN M. CHENEY.
